TRANSPORTABLE RESTROOM

RELATED APPLICATION

This is a continuation-in-part of application Ser. No. 13/759,803, filed on Feb. 5, 2013, now U.S. Pat. No. 9,340,963, the priority benefit of which is hereby claimed.

FIELD OF THE INVENTION

The present invention is generally directed to portable toilets and in particular to transportable toilets for temporary use in places where municipal sewer hookups are not available.

SUMMARY OF THE INVENTION

The present invention provides a transportable restroom comprising a rectangular skid; a clean water tank carried by the skid and a waste water tank carried by the skid and disposed side to side on the skid to form a unitary base; wall extending from the base including a door; roof over the wall; and a toilet disposed over the waste water tank. The skid includes a recess with triangular wall portions. The waste water tank includes a bottom with corresponding triangular wall portions; and the waste water tank is disposed within the recess.

The present invention further provides transportable restroom, comprising: a skid and a clean water tank and a waste water tank carried by the skid. The waste water tank includes an access opening for removing contents from the waste water tank and a cover over the access opening. The access opening includes a peripheral edge with a groove for receiving water; and the cover includes a peripheral projection for being received within the groove.

The present invention further provides a transportable restroom, comprising a skid supporting the transportable restroom; the skid including a bottom with a slot across the bottom; a first recess centered at a front side of the skid and a second recess centered at a rear side of the skid. A longitudinal member is disposed in the slot and first and second wheels are attached to the longitudinal member to support the restroom on the first and second wheels; and a handle with a third wheel at one end and a projecting member above the third wheel. The projecting member when inserted in the first recess or the second recess is effective to raise the front side or the rear side, respectively, when the handle is rotated downwardly and support the restroom on the third wheel for hauling the restroom to a desired location.

The present invention also provides a transportable restroom, comprising a skid; a clean water tank and a waste water tank carried by the skid and disposed side to side on the skid to form a unitary base; wall extending from the base including a door; roof over the wall; and a toilet disposed over the waste water tank. The walls include an outer wall, an inner wall and a radiant barrier. The outer wall is spaced from the inner wall; and the radiant barrier is disposed between the outer wall and the inner wall.

The present invention further provides a transportable restroom, comprising a skid; a clean water tank and a waste water tank carried by the skid disposed side to side on the skid to form a unitary base; a battery housing carried by the waste water tank. The battery housing includes an outer wall, an inner wall and a radiant barrier. The outer wall is spaced from the inner wall; and the radiant barrier is disposed between the outer wall and the inner wall.

2

The present invention provides a transportable restroom, comprising a skid; a clean water tank and a waste water tank carried by the skid and disposed side to side on the skid to form a unitary base; the extending from the base including a door; roof over the wall; a toilet disposed over the waste water tank; and a solar panel positionable over the roof when deployed. The solar panel is positionable vertically adjacent the wall for transport.

10 BRIEF DESCRIPTION OF THE DRAWINGS

FIG. 1 is a perspective view of a transportable restroom with portions shown broken away, embodying the present invention.

15 FIG. 2 is a top perspective view of a skid embodying the present invention.

FIG. 3 is a bottom perspective view of the skid shown in FIG. 1.

20 FIG. 4 is a top perspective view of a clean water tank embodying the present invention.

FIG. 5 is a bottom perspective view of the clean water tank shown in FIG. 4.

25 FIG. 6 is a top perspective view of a waste water tank embodying the present invention.

FIG. 7 is a bottom perspective view of the waste water tank shown in FIG. 6.

FIG. 8 is a side elevational view of the waste water tank shown in FIG. 6.

30 FIG. 9 is a rear top perspective view of the clean water tank and the waste water tank nested together on top of the skid to form a unitary base.

FIG. 10 is a side elevational view of the transportable restroom of FIG. 1, showing a solar panel in a deployed position.

35 FIG. 11 is a perspective assembly drawing of a wall construction of the transportable restroom embodying the present invention.

FIG. 12 is an edge perspective view of the wall construction shown in FIG. 11.

40 FIG. 13 is a perspective cross-sectional view taken along line 13-13 in FIG. 10.

FIG. 14 is a perspective cross-sectional view taken along line 14-14 in FIG. 10.

45 FIG. 15 is a perspective view of a roof structure of the transportable restroom embodying the present invention.

FIG. 16 is side elevational view of the transportable restroom of FIG. 1, showing the solar panel in a transport position.

50 FIG. 17 is a perspective view of the solar panel in the deployed position.

FIG. 18 is perspective view of a side of the transportable restroom of FIG. 1, showing a pin used to place the solar panel in the transport position.

55 FIG. 19 is a front top perspective view of the unitary base shown in FIG. 9, showing a dolly system for moving the transportable restroom.

FIG. 20 is a cross-sectional view showing the engagement of a wheeled handle with the underside of the skid.

60 FIG. 21 is a side elevational view showing the lifting of the front end of the unitary base to allow insertion of a carriage underneath the base.

FIG. 22 is a side elevational view of the unitary base showing the act of inserting the wheeled handle at the rear end of the base.

65 FIG. 23 is a side elevational view of the unitary base lifted from the ground and ready to be wheeled away.

FIG. 24 is a perspective view of a handle with a wheel and a disc to be placed underneath the wheel.

FIG. 25 is a perspective view of a pair of wheels riding on respective discs.

FIG. 26 is a perspective view with portions shown in cross-section showing a disc supporting a wheel.

FIG. 27 is a perspective view of a disc.

FIG. 28 is a top view of a disc.

FIG. 29 is front end view of the disc of FIG. 28.

FIG. 30 is a side elevational view of the disc of FIG. 28.

FIG. 31 is a perspective view of a cover and a wall of battery housing.

FIG. 32 is a cross-sectional view of a wall and a cover of battery housing, showing radiant barrier sheets inside the wall and the cover.

FIG. 33 is perspective view of a cover over an access opening of a waste water tank.

FIG. 34 is a cross-sectional view of the cover and the access opening of FIG. 33.

FIG. 35 is a cross-sectional view of the cover and the access opening of FIG. 33, showing the cover being opened.

FIG. 36 is a plumbing schematic of the restroom of FIG. 1.

DETAILED DESCRIPTION OF THE INVENTION

Referring to FIG. 1, a transportable and self-contained restroom 2 is disclosed in U.S. Pat. No. 9,340,963, hereby incorporated by reference. The restroom 2 includes a preferably one-piece molded rectangular skid 4 configured for lifting by a standard forklift (not shown) for loading onto and unloading from a truck for transport to a site where the restroom 2 is to be used. The skid 4 includes slots 5 for receiving the lifting arms of the forklift. The forklift may also be used for positioning the restroom 2 at a specific location at the site. A one-piece molded clean water tank 6 and a one-piece molded waste water tank 8 are disposed on the skid 4. The clean water tank 6 and the waste water tank 8 are separate (not connected) and independent from each other so that a leak in one tank will not affect the other tank. The tanks 6 and 8 nest or mate together over the skid 4 to form a rectangular base 7 for the restroom 2. A sheet 19 made of plastic or other suitable material is laid on top of the tanks 6 and 8 to advantageously provide a flat and continuous surface to cover the breaks and crannies on the top walls of tanks and aid in clean-up with water spraying.

The restroom 2 has walls 11 on three sides (one wall is shown), a door 13, a roof 17, a toilet 15 and a hand wash 9. The walls 11 are attached to a U-shaped member 23 attached to the top wall of water tanks.

The weight of the clean water tank 6 or the waste water tank 8 when full and their lower location with respect to the ground advantageously anchors the restroom to the ground and advantageously provide a lower center of gravity for the restroom 2 for stability.

Referring to FIG. 2, the skid 4 includes a peripheral flange 10 that mates with a peripheral step 12 (see FIGS. 5 and 7) along the outer bottom edges of the tanks 6 and 8. The flange 10 advantageously keeps the tanks 6 and 8 contained within the outer boundary of the skid 4. The skid 4 includes a top horizontal flat wall 14 and a recess 16 formed from triangular wall portions 18 joined to form an inverted pyramid. The flat wall 14 supports the clean water tank 6. The recess 16 extends downwardly from below the level of the wall 14. The triangular wall portions 18 support the waste water tank 8.

The lowest part of the bottom of the recess 16 has an opening 20 for draining water to the ground. An opening 21 communicates with the top wall 14 for draining water to the ground. Bosses 22 are provided for attachment of the waste water tank 8 to the skid 4. Holes 23 are provided for attachment of the clean water tank 6 to the skid 4. Flange portions 26 at the front and rear of the skid 4 are provided for securing with respective Z-bars 28 (one is shown) attached to a flatbed trailer to keep the restroom 2 secured to the flatbed trailer during transport. The restroom 2 slides into or out of the Z-bars 28.

Referring to FIG. 3, the underside of the skid 4 is shown. The slots 5 extend through the width of the skid. Several kiss-offs 30 help support the weight of the tanks 6 and 8 and transfer the weight to the ground. The bottom of the skid includes several flat walls 32 for maximum surface contact with the ground for effective support of the weight of the restroom 2. The bosses 22 are supported by vertical walls 40 to transmit the weight of the waste water tank 8 to the ground.

Referring to FIG. 4, the clean water tank 6 includes a slot 33 into which the waste water tank 8 is nested. The slot 33 includes sides 34, 36 and 38. Flange portions 42 are provided around the outer periphery of the tank 6 for attachment of the U-shaped member 23, which is used to attach the walls 11. Slots 46 that communicate with the interior of the restroom 2 and the outside are provided along one side of the clean water tank 6. The slots 46 advantageously allow water used to clean the inside of the restroom 2 to flow to the outside. The slots 46 are also used to draw air from the outside into the interior of a double-space wall as will be described below. Fresh water fill port 48 is provided with a recess 50 with a strainer for salt pellets for use during cold weather to prevent water freezing. A top wall 49 receives a user as he/she enters the door 13 disposed above the side 55. The fill port 48 is advantageously located outside the walls 11 so that the clean water tank 6 can be refilled without going inside the restroom 2.

Referring to FIG. 5, the clean water tank 6 includes a flat bottom wall 51 that mates with the flat top wall 14 of the skid 4, advantageously supporting the clean water 6 with maximum surface contact. Conical walls 53 as disclosed in U.S. Pat. No. 9,340,963 provide support to the top wall 49, transferring the load of the tank and the user to the skid and to the ground.

Referring to FIG. 6, the waste water tank 8 includes sides 52, 54 and 56 that mate with respective sides 34, 36 and 38 of the clean water tank 6. Flanges 60 are provided for mounting the U-shaped member 23. A housing 62 for a battery is provided at one end of the waste water tank. An access 64 into the interior of the waste water tank 8 permits vacuuming and cleaning of the waste water tank. An openable cover 66 keeps the access closed to keep odor in. An opening 68 into the waste water tank 8 is configured to receive the outlet of the toilet 15. Slots 69 that communicate with the interior of the restroom 2 and the outside are provided along one side of the waste water tank 8. The slots 69 advantageously allow water used to clean the inside of the restroom 2 to drain to the outside. The slots 69 are also used to draw air from the outside into the interior of a double-space wall as will be described below.

Referring to FIG. 7, a bottom perspective view of the waste water tank 8 is disclosed. The bottom wall 70 is made up of several triangular shaped wall portions 72 descending downwardly to a common low point to form an inverted pyramid shape. The wall portions 72 mate with the corresponding wall portions 18 of the skid 4. The wall portions 72

meet at an apex 74, which is substantially below the opening 69, thereby allowing the waste solids to accumulate in the lowest point of the waste water tank 8 for easier cleaning. Horizontal pads 76 are disposed within respective recesses 78, which are configured to receive the respective bosses 22 on the skid 4. Through-openings 80 are aligned with the openings 21 in the skid 4 to allow for drainage of cleaning water.

Referring to FIG. 8, the bottom wall 70 of the waste water tank 8 is shown angled downwardly toward the apex 74. The angle of inclination from the horizontal is configured to provide a larger capacity for the waste water tank 8 and for easier cleaning, since the waste solids will tend to settle toward the apex 74, which is at a line of sight from the access 64 when the door 66 is opened. The apex 74 is advantageously disposed below the toilet opening 68 so that waste solids will drop directly into the apex 74. Rinse water used for spraying the interior of the tank 8 would also drain readily toward the apex 74 for easier vacuuming. The access 64 is advantageously located outside the walls 11 and is, therefore, accessible from the outside.

Referring to FIG. 9, the clean water tank 6 and the waste water 8 are shown nested to each other over the skid 4 to form a unitary base. An openable cover 82 is provided for the housing 62 for access to the battery for maintenance or replacement. The side 36 of the clean water tank 6 is configured to abut and engage the sides 54 of the waste water tank 8 for rigidity to the top wall 49 to provide support to the user when he/she enters the restroom 2 and steps over the top wall 49. The vertical walls on the sides 36 and 54 when they are nested together advantageously provide additional load bearing strength for a user standing on or near the sides 36 and 54 to resist shear and compression loads.

Referring to FIGS. 10, 11 and 12, the wall 11 is a double-space wall construction with an outer wall 84, an inner wall 86 spaced from the outer wall 84 with an intermediate radiant barrier 88 in between. The inner wall 86 includes a plurality of projections 90 space the radiant barrier 88 away from the inner wall 86. A plurality of ribs 92 extends inwardly into the interior space of the wall 11 to space the radiant barrier 88 away from the outer wall 84. The resulting assembly provides air space 94 between the inner wall 86 and radiant barrier 88 and air space 96 between the outer wall 84 and the radiant barrier 88. The air spaces 94 and 96 promote convection air flow to carry heat impinging on the outer wall 84 to the outside. The radiant barrier 88, which is preferably made of an aluminum foil layer over a polyethylene sheet, commercially available from ASTRO-FOIL International, is disposed inside the wall 11 such that the foil layer faces the outer wall 84 to reflect radiation away from the inner wall 86. The air spaces 94 and 96 are preferably each about 0.75 inches. Hot air flows 95 and 97 in the respective spaces 94 and 96 advantageously help moderate the temperature inside the restroom 2 against the solar radiation 99 impinging on the wall 11.

Referring to FIGS. 13 and 14, cool air flow 98 enters the spaces 94 and 96 through the respective slots 69 along the side of the waste water tank 8 and the slots 46 along the side of the clean water tank 6 and exits out through a vent 100 in the roof 17. The cool air flow 98 absorbs the heat within the spaces 94 and 96 as it flows upwardly before discharging through the opening 100 at the roof. Accordingly, the double-space construction of the wall 11 helps prevent the interior of the restroom 2 from overheating.

The roof 17 includes an outer wall 102 spaced from an inner wall 104, creating a space 106 for the air flow 98 from the bottom of the wall 11. A radiant barrier 108 is disposed

between spacer ribs 110 to create a space 115 between the inner wall 104 and the radiant barrier 108. Another space 113 between the radiant barrier and the outer wall 102 may also be created. The outer wall 102 is disposed over the radiant barrier 108. The radiant barrier 108, which is preferably made of an aluminum foil layer over a polyethylene sheet, commercially available from ASTRO-FOIL International, is adhered over the spacer ribs 110 such that the foil layer faces the outer wall 102 to reflect radiation away from the inner wall 104. The spaces 106 and 113 communicate with the spaces 94 and 96 in the wall 11 to allow the flow of hot air to exit through the vent 100.

An electric fan 112 disposed at the roof 17 provides additional ventilation inside the restroom 2. Cool air is drawn through the bottom slots 69 and 46 and out through a vent opening 100 to the outside under a cover 114.

Referring to FIGS. 10, 16 and 17, a solar panel 116 is positionable between a transport position and a deployed position. The solar panel is pivotably attached to the roof 17 at pivots 118. When in the transport position, the solar panel 116 is disposed vertically downwardly from the pivots 118, substantially close to the rear wall of the restroom 2. The solar panel 116 is rotatable by more than 180° from the deployed position to the transport position to advantageously position the operative face of the solar panel close to the rear wall of the restroom for protection during transport. When in the deployed position, the solar panel 116 is angled toward the sun to receive maximum solar radiation, preferably between 10° to 40° from the horizontal plane. A pair of attachment portions 120 molded into the roof 17 (one is visible) support the pivots 118. An arm 122 with multiple holes 124 has one end 126 pivotably attached to an opposite corner of the solar panel 116 with pivot 128. A pin 130 attached to an upper edge of the wall 11 a distance from the pivot 118 is used to receive one of the holes 124 to properly position the solar panel 116 toward the sun. A pin 132 disposed at lower portion of the wall 11 is used to secure the arm 122 when the solar panel 116 is the transport position. The operative face of the solar panel 116 is advantageously toward the wall 11 when in the transport position for protection. When deployed, the solar panel 116 is used to charge the battery.

Referring to FIG. 19, a pair of wheels 134 attached to a longitudinal member 136 and a handle 138 with a wheel 140 at one end 142 may be used to move the restroom 2 to its final position after having been unloaded from a truck. The skid 4 has a recess 144 centered at the front side and an identical recess 145 centered at the rear side (see FIG. 3). One of the wheels 134 is attached to collar 135 which is slidable along the member 136 to shorten or lengthen the distance between the wheels 134 depending on the width of the lift gate of the truck used to transport the restroom 2. The collar 135 may be locked in place with a set screw 137 (see FIG. 25).

The wheels 134 and 140 are used on hard surfaces, such as asphalt or concrete. For sandy surfaces or soft dirt, convex shaped discs 158 are placed underneath the respective wheels to advantageously distribute the weight of the restroom over the larger surface area of the discs.

Referring to FIG. 20, the handle 138 is bent at an intermediate portion 146. The end 142 includes a bent portion 148 and a cross-member 150. The other end of the handle 138 has a cross-member 152 for convenient gripping by the user.

Referring to FIG. 20 with the understanding that the structure disclosed for the recess 145 is identical to the recess 144, when the end 142 is inserted into the recess 145,

the cross-member 150 engages a support wall 154 of the recess 145 disposed at a distance above the bottom surface 156 of the skid 4 less than the distance between the cross-member 150 and the bottom of the wheel 140. Consequently, pushing the handle 138 downwardly is effective to lift the surface 156 above the ground, providing enough clearance to slip the wheels 134 into the slot 5 thereby to place the wheel 134 underneath the skid 4. The wheels 134 may then be positioned in the slot 5 lifted above the ground by the handle 138. Once the wheels 134 are positioned in the slot 5, the handle 138 is removed from the recess 145 and inserted in the recess 144 at the front of the skid 4 to lift it, as shown in FIGS. 22 and 23. The handle 138 is then pulled to move the restroom 2. The operation may be reversed, starting with the recess 144 and then with the recess 145 and then pulling the restroom 2 at the rear end.

Referring to FIGS. 24-26, the wheel 140 is pivotable about a vertical axis in the direction 143 to allow the operator to guide the wheel 140 in the desired direction. The discs 158 are disposed underneath the respective wheels 134 and 140 so that a concave surface 160 is presented to the dirt or sand in the direction 162 the restroom is pulled. Each of the discs 158 has wheel receiver 164 that holds the respective wheel at rear portion 166 inside the disc so that the leading surface 160 of the disc is lifted up to skim over the sand or dirt when the restroom is pulled.

Referring to FIGS. 27-30, the disc 158 is shaped like a dish with a continuously convex bottom surface 168 and a curved peripheral edge 170. The receiver 164 has front wall 172 and side walls 174. The receiver 164 is disposed at the rear portion 166 of the disc, with side walls 174 extending beyond the rear edge 176 of the disc, allowing the side walls 174 to be guided to receive the respective wheel before the wheel is pulled onto the disc. The weight of the restroom bearing on the rear portion of the discs 158 through the respective wheels advantageously keeps the leading surface 160 raised up to slide over the sand or dirt.

The discs 158 can have any shape when viewed from the top, such as ski shaped, as long as the weight of the restroom is distributed over the larger surface area of the discs and they can glide over the sand or dirt.

Referring to FIGS. 31 and 32, the battery housing 62 has side wall 178 and a cover 82. The cover 82 has an inner wall 179 and an outer wall 181. The side wall 178 has an inner wall 183 and an outer wall 185. The cover 82 and side wall 178 are provided with slots 180 for insertion of radiant barrier sheets 182 into the interior space of the side wall 178 and the cover 82. The radiant barrier sheets 182 advantageously reflect radiant heat from the sun away from the battery inside the housing 62. The radiant barrier sheet 182 is preferably made of an aluminum foil layer over a polyethylene sheet, commercially available from ASTRO-FOIL International. The aluminum foil advantageously reflects radiant heat away from the interior of the battery housing 62. The barrier sheets 182 helps to keep the battery from overheating when the battery housing 62 is exposed to the sun.

Referring to FIGS. 33 and 35, an access 187 into the interior of the waste water tank that advantageously keeps the odor from escaping to the outside is disclosed. The access 187 includes a cover 184 and a groove 186 disposed around the periphery of the access opening 188. The groove 186 is horizontal so that water will fill the entire course of the groove. A projection 190 extends downwardly from the underside of the cover 184 and is disposed within the groove 186 when the cover is closed. The projection 190 makes a complete circuit and uninterrupted run within the groove

186. When the groove 186 is filled with water, the lower edge portion 192 of the projection 190 is immersed in the water, thereby blocking the path of air from the interior of the waste water tank 8 to the outside. Odor is kept within the waste water tank 8 since the path of air from the interior would follow the interior surface of the cover 184 and the projection 190 that is blocked by the water within the groove 186. The projection 190 may be wedge shaped with a vertical side 191 and a ramped side 193, but can be any shape as long as the lower edge portion 192 is completely immersed in the water within the groove 186.

A hinge 194 attaches the cover 184 to the tank 8. A pin 196 attached to the cover 184 is captured within an inclined slot 198. The cover 184 is opened by pulling on the cover horizontally, causing the pin 196 to ride on the slot 198 and the ramped side 193 on the upper edge 202 of the groove 186. The displacement of the cover along the slot 198 serves to clear the projection 190 from the groove 186 so that the cover can then be rotated and opened.

Referring to FIG. 36, a plumbing circuit for the restroom 2 is disclosed. Water from the clean water tank 6 is fed to the toilet 15 via a strainer and check valve 203 to a filter 204 and an electric pump 206 powered by a battery. Water from the clean water tank 6 is also fed to the hand wash 9 via a foot pump 208. Waste water from the toilet and the hand wash flows into the waste water tank 8.

While this invention has been described as having preferred design, it is understood that it is capable of further modification, uses and/or adaptations following in general the principle of the invention and including such departures from the present disclosure as come within known or customary practice in the art to which the invention pertains, and as may be applied to the essential features set forth, and fall within the scope of the invention or the limits of the appended claims.

We claim:

1. A transportable restroom, comprising:
  - a skid;
  - a clean water tank carried by said skid;
  - a waste water tank carried by said skid;
  - 40 said clean water tank and said waste water tank are disposed side to side on said skid to form a unitary base;
  - 45 e) wall extending from said base including a door;
  - f) a roof over said wall;
  - g) a toilet disposed over said waste water tank;
  - h) said the skid including a recess;
  - i) the waste water tank including a bottom;
  - j) said bottom of said waste water tank is disposed within said recess;
  - k) said clean water tank and said waste water tank including outer edge portions; and
  - 50 l) flanges disposed on said outer edge portions.
2. A transportable restroom as in claim 1, wherein:
  - a) said clean water tank and said waste water tank include top walls above said flanges;
  - b) said clean water tank and said waste water tank include drainage slots along said outer edge portions; and
  - c) said drainage slots extend from said top walls to said flanges.
3. A transportable restroom as in claim 1, wherein:
  - a) said skid includes a flat top wall portion; and
  - b) said clean water tank is disposed over said flat top wall portion.
4. A transportable restroom as in claim 1, wherein said recess includes an opening for water drainage.

5. A transportable restroom as in claim 1, wherein:
- 5 said skid includes front side and a rear side; and
  - 5 said skid includes a flange at said front side and said rear side.
6. A transportable restroom as in claim 1, wherein:
- 10 said bottom of said waste water tank includes a low point; and
  - 10 b) an opening into said waste water tank for said toilet is disposed above said low point.
7. A transportable restroom as in claim 6, wherein:
- 15 said waste water tank includes an access opening for cleaning; and
  - 15 b) said access opening and said low point is along a line of sight of a maintenance person.
8. A transportable restroom as in claim 1, wherein:
- 20 said wall includes an outer wall, an inner wall and a radiant barrier;
  - 20 b) said outer wall is spaced from said inner wall; and
  - 20 c) said radiant barrier is disposed between said outer wall and said inner wall, said radiant barrier is spaced from said outer wall and said inner wall.
9. A transportable restroom as in claim 8, wherein:
- 25 said roof includes an outer wall and an inner wall, said outer wall of said roof is spaced from said inner wall of said roof; and
  - 25 b) a space between said outer wall and said inner wall of said roof communicates with an interior space in said wall extending from said base.
10. A transportable restroom as in claim 1, and further comprising:
- 30 a) a solar panel positionable over said roof when deployed; and
  - 30 b) said solar panel is positionable vertically adjacent said wall for transport.
11. A transportable restroom as in claim 10, wherein said solar panel is adjustable in inclination relative to a horizontal plane when deployed.
12. A transportable restroom as in claim 10, wherein said solar panel is rotatable greater than 180° from a deployed position to a transport position.
13. A transportable restroom as in claim 1, and further comprising:
- 35 a) a pair of wheels disposed below said skid at a first end of said skid to elevate said first end above the ground; and
  - 35 b) a handle with a wheel at one end disposed below said skid at a second end opposite to said first end of said skid to elevate said second end above the ground.
14. A transportable restroom as in claim 13, wherein a distance between said pair of wheels is adjustable.
15. A transportable restroom as in claim 13, and further comprising:
- 45 a) convex shaped disc disposed underneath each of said wheels; and
  - 45 b) said disc includes a leading portion raised upwardly when pulling said restroom.
16. A transportable restroom as in claim 1, wherein:
- 50 a) said waste water tank includes an access opening for cleaning;
  - 50 b) a cover over said access opening;
  - 50 c) said access opening includes a peripheral edge with a groove for receiving water; and
  - 50 d) said cover includes a peripheral projection for being received within said groove.
17. A transportable restroom as in claim 16, wherein said projection is wedge shaped.

18. A transportable restroom as in claim 1, wherein:
- 5 said clean water tank includes slots along one side for water drainage;
  - 5 b) said waste water tank includes slots along one side for water drainage; and
  - 5 c) said slots of said clean water tank and said waste water tank communicate with an interior space of said wall.
19. A transportable restroom as in claim 1, and further comprising:
- 10 a) a battery housing;
  - 10 b) said battery housing including an outer wall, an inner wall and a radiant barrier;
  - 10 c) said outer wall is spaced from said inner wall; and
  - 10 d) said radiant barrier is disposed between said outer wall and said inner wall.
20. A transportable restroom as in claim 19, wherein said battery housing is carried by said waste water tank.
21. A transportable restroom, as in claim 1, and further comprising:
- 15 a) an electric fan disposed in an opening in said roof to exhaust air from the inside of said restroom to the outside of said restroom; and
  - 15 b) a cap disposed over said opening, said cap including a downwardly extending peripheral wall having a bottom edge spaced apart from said roof to provide an outlet to the outside for the air being exhausted from the inside of said restroom.
22. A transportable restroom as in claim 1, wherein:
- 20 a) said recess includes triangular wall portions;
  - 20 b) said bottom includes triangular wall portions; and
  - 20 c) said triangular wall portions of said recess mate with said triangular wall portions of said bottom.
23. A transportable restroom, comprising:
- 25 a) a skid supporting said transportable restroom, said skid including a bottom with a slot across said bottom, said skid including a first recess centered at a front side of said skid, said skid including a second recess centered at a rear side of said skid;
  - 25 b) a longitudinal member disposed in said slot;
  - 25 c) first and second wheels attached to said longitudinal member to support the restroom on said first and second wheels; and
  - 25 d) a handle with a third wheel at one end and a projecting member above said third wheel;
  - 25 e) said projecting member when inserted in said first recess or said second recess is effective to raise said front side or said rear side, respectively, when said handle is rotated downwardly and support said restroom on said third wheel for hauling said restroom to a desired location.
24. A transportable restroom as in claim 23, wherein a position of one of said first and second wheels is adjustable with respect to said longitudinal member.
25. A transportable restroom as in claim 23, and further comprising:
- 30 a) convex shaped discs disposed underneath respective said first, second and third wheels; and
  - 30 b) said discs include respective leading portions raised upwardly when pulling said restroom.
26. A transportable restroom, comprising:
- 35 a) a skid;
  - 35 b) a clean water tank carried by said skid;
  - 35 c) a waste water tank carried by said skid;
  - 35 d) said clean water tank and said waste water tank are disposed side to side on said skid to form a unitary base;
  - 35 e) wall extending from said base including a door;
  - 35 f) roof over said wall;

- g) a toilet disposed over said waste water tank;
- h) said the skid including a recess;
- i) the waste water tank including a bottom disposed in said recess;
- j) a pair of wheels disposed below said skid at a first end of said skid to elevate said first end above the ground; and
- k) a handle with a wheel at one end disposed below said skid at a second end opposite to said first end of said skid to elevate said second end above the ground. 10
